DES. 2165

Alvan L. Jewell of Waltham Mass.
Letters Patent No. 9165 Dated Sept 19, 1875
Design for a Wind Vane

The schedule referred to in these Letters Patent and making part of the same:

To all Persons to whom these Presents shall come,

Be it known that I, Alvan L. Jewell
of Waltham, in the County of Middlesex, and State of Mas-
sachusetts, have invented or produced an ornamental
Design for a weather or wind vane; and I do hereby
declare the same to be fully described in the following
specification, and represented in the accompanying drawing.

The design is the Goddess of Liberty holding an
American Flag by its staff.

The design consists of a female dressed in a short
tunic, a and a skirt, b, and not only having a liberty cap, c,
on her head encompassed by a wreath of laurel, but also
a dash, d, with stars on it, going around from one shoulder
down to the waist below the other shoulder. One arm is
stretched out horizontally, or about so, and the other is bent
upward and supports the staff, e, of a flag, f, the whole
being as shown in the drawing.

I claim as my invention, the said design for
a weather or wind vane, the whole being as described
and represented.
